United States Patent Office

Des. 183,147
Patented July 1, 1958

183,147

WHEEL COVER

Joseph R. Schemansky, Birmingham, Mich., assignor to,
General Motors Corporation, Detroit, Mich., a cor-
poration of Delaware

Application December 28, 1956, Serial No. 44,350

Term of patent 7 years

(Cl. D14—30)

Figure 1 is a front elevational view of a wheel cover embodying my new design;

Figure 2 is a side elevational view;

Figure 3 is a sectional view taken on the plane indicated by line 3—3 of Figure 1; and

Figure 4 is a perspective view.

I claim:

The ornamental design for a wheel cover, substantially as shown.
